UNITED STATES PATENT OFFICE.

WILLIAM W. LOWREY, OF NEW YORK, N. Y.

DESIGN FOR A GLASS BOTTLE.

SPECIFICATION forming part of Design No. 30,760, dated May 16, 1899.

Application filed April 24, 1899. Serial No. 714,321. Term of patent 3½ years.

To all whom it may concern:

Be it known that I, WILLIAM W. LOWREY, a citizen of the United States, residing at Stuyvesant Place, in the borough of Richmond, 5 city and State of New York, have invented and produced a new and original Design for Glass Bottles, of which the following is a specification, reference being had to the accompanying drawings, forming part thereof.

10 Figure 1 is a front elevation showing my design. Fig. 2 is a plan view thereof, as shown in the drawings.

15 The leading and material feature of my design consists of the bulge or round cornered tablets A, forming, as they do, the four sides of the bottle. These bulges A are represented

as rising from the planes B, forming the vertical shaft or body of the bottle. The aforesaid planes B are surmounted with the convex-shaped portion C, from which the neck 20 of the bottle rises, the lower edges of the vertical planes B terminating in the base of the structure.

Having described my invention, what I claim as new, and desire to secure by Letters 25 Patent, is—

The design for a glass bottle as herein shown and described.

WILLIAM W. LOWREY.
